Primary Examiner — Janice Hallmark(74) *Attorney, Agent, or Firm* — McGarry Bair PC(57) **CLAIM**

The ornamental design for a ceiling fan light glass, as shown and described.

DESCRIPTION

FIG. 1 is a top perspective view of a ceiling fan light glass showing my new design;

FIG. 2 is a bottom perspective view thereof;

FIG. 3 is a top view thereof;

FIG. 4 is a bottom view thereof;

FIG. 5 is a front side view thereof;

FIG. 6 is a left side view thereof;

FIG. 7 is a rear view thereof; and,

FIG. 8 is a right side view thereof.

The broken lines in FIG. 1 showing a ceiling fan and the broken lines in FIGS. 2-8 showing a ceiling fan light kit, depict environmental subject matter only and form no part of the claimed design. The broken lines surrounded by claimed subject matter depict portions of the ceiling fan light glass that form no part of the claimed design.
